UNITED STATES PATENT OFFICE.

FREDERICK W. SAUER, OF BROOKLYN, NEW YORK.

SHEET-FEEDER FOR PRINTING-PRESSES.

1,264,211.

Specification of Letters Patent. Patented Apr. 30, 1918.

Application filed July 5, 1917. Serial No. 178,626.

To all whom it may concern:

Be it known that I, FREDERICK W. SAUER, a citizen of the United States, residing in the borough of Brooklyn, city of New York, county of Kings, and State of New York, have invented new and useful Improvements in Sheet-Feeders for Printing-Presses, of which the following is a specification.

10 The invention relates to sheet feeders for printing presses, and the object is to provide novel and efficient means for separating the top sheet from the balance of the pile preparatory to the advancing movement. The invention includes a pneumatic separator having a compound rocking and sliding movement constructed to turn up and lift the rear edge of the sheet, and a mechanical detent which operates in alternation with the separator to engage and hold the next top sheet beneath the lifted edge. The various novel features of construction, relation and operation will appear as the specification proceeds.

25 In the accompanying drawings:

Figure 1 is a side elevation of the co-ordinated instrumentalities over the rear portion of the stack together with their supporting means and operating connections. The supporting bar is shown broken away, for economy of space; the stack of sheets is represented by the rear portion only of a few of the top sheets; the separator is shown in the act of turning up the rear edge of the top sheet preparatory to lifting it; and the detent is in its retired position.

40 Fig. 2 is a view on a larger scale and largely in vertical section showing the separator in its raised position, having released the top sheet, and the detent in its forwardly depressed position bearing upon the balance of the stack;

Fig. 3 is a sectional plan taken on the line 3—3 of Fig. 1, indicating driving means for operating the coöordinated devices;

45 Fig. 4 is a face view of the mouthpiece of the separator with the barrel wherein it is mounted in section;

Fig. 5 is a top perspective view of the 50 mouthpiece;

Fig. 6 is a perspective view of the rocking holder for the separator;

Fig. 7 is a rear elevation of the mechanism;

Fig. 8 is a transverse section on the line 55 8—8 of Fig. 2; and

Fig. 9 is a simplified view, on a reduced scale, illustrating the relations.

In the frame 2 (Fig. 9) is a suitable table 3 or support for the stack of sheets 4. This 60 table, it will be understood, is provided with means, as is customary, for raising it as the sheets are fed, to maintain a substantially constant top level. Over the front of the stack is located the means for 65 advancing the successive sheets. Such means is designated generally 5 and may be of the character disclosed in Patent 1,105,352 of July 28, 1914.

Extending transversely between the side 70 members of the main frame 2, at a distance above the stack, are forward and rearward rods 6 and 7. Upon these are mounted a supporting superstructure for the separator and detent mechanism. Preferably 75 said superstructure comprises a central longitudinal bar 8, which is pivotally mounted at its forward end upon the rod 6 and has an up and down adjusting connection at the rear with the rod 7. In the 80 particular construction shown a U bracket 9 is secured to the top of the bar 8 at its rear end, to receive a screw 10, which is threaded downward through its top and has a pivotal swivel connection at its lower end 85 with the rod 7. Said connection is preferably formed by means of a ball 11 fixed to the lower end of the screw and capable of turning in a corresponding socket in the rod, wherein it is retained by a cap 12. 90

The upper end of the screw carries an operating handle 13, beneath which there may be a lock nut 14 adapted to be screwed down upon the top of the bracket 9 to hold the adjustment. The interior opening of the 95 U bracket preferably registers with a notch in the top of the bar 8, the two together constituting an elongated clearance space 15 capable of accommodating the cross rod 7 within a substantial range of vertical adjustment.

Upon the bar 8, somewhat in advance of its rear end, is a supporting block 16, which may be made in two vertical halves, receiving the bar between their upper portions, 105 which are suitably recessed for the purpose, and united by screws 17. The block thus constructed has a sliding fit upon the bar,

to which it may be locked at any desired point of longitudinal adjustment by set screws 18. A rear supporting block 19 is supported slidably upon the under portion 5 of the bar, beneath the rod 7, by means of a dove-tail way 20 on the bar and corresponding recess in the top of the block, which recess is somewhat wider than the way to accommodate a gib 21, which may 10 be pressed against the guideway by screws 22. This block has at the rear a depending socket 23, which receives the vertical stem 24 of a guide block 25, the stem being clamped in the socket by a lateral set screw 15 26, affording another means of vertical adjustment. The function of the guide block 25 will be described hereinafter.

The lower portion 27 of the halves of the supporting block 16 are separated laterally 20 to form a supporting yoke wherein is mounted a rocker block 28, constituting a holder for the pneumatic separator device. A tube 29, passing through and rotatably mounted in the lower ends of the side members 25 27 of the yoke, constitutes the pivot for the rocker and a section of the conduit whereby the separator is connected with a region of negative air pressure (not shown). A further section of this conduit is illustrated at 30, the same being an exterior pipe terminating in a stationary block 31, which encircles the hollow pivot 29 between one of the side members 27 and a retaining cap 32 which is secured to the end of the 35 pivot tube by a screw 33. A port 34 in the side of the tube 29 at this end is in communication with the opening through the block 31 from the conduit section 30, and is preferably of sufficient length to remain in 40 open communication therewith irrespective of the oscillation of the pivot. Upon the opposite end of the pivot tube is fixed the hub of an operating arm 35, from which a link 36 extends into operative relation to a 45 cam or eccentric 37, or other element of an external train of driving mechanism, which it is not necessary to illustrate. By means of the cam and linkage or other suitable mechanism for imparting oscillatory movement, the rocker 28 is swung back and forth 50 through a limited range, the extremities of which are represented approximately in Figs. 1 and 2.

As more particularly illustrated in Fig. 55 6 the upper portion of the rocker block 28 is slotted in a vertical longitudinal plane, and at the lower end of this slot 38 is a fore and aft bore 39 having an opening 40 in its bottom leading into the transverse 60 pivot bore 41, wherein the tube 29 is secured by a set screw 42. In the bore 39 is received a slidable tubular arm 43, one end of which is closed and the opposite end of which carries a transverse suction mouthpiece 44. A port 45 is cut in the lower side

of the tubular arm 43 for the purpose of communicating through the opening 40 with a port 46 in the pivot tube 29. It is intended that the suction through the mouthpiece shall be intermittent, which is accomplished by causing ports in relatively movable members of the suction conduit to pass into and out of communication with each other at the proper times in the cycle of operations. This is advantageously provided for by so proportioning and arranging the port 45 that it passes into and out of communication with the port 46 with the reciprocation of the tubular arm 43. Thus, in the retracted position of the arm shown 80 in Fig. 2, the passage of air is interrupted, whereas in the projected position of Fig. 1 the communication is open and suction exists at the mouthpiece.

The preferred embodiment of mechanism 85 for causing the arm 43 of the pneumatic separator to reciprocate longitudinally simultaneously with its tilting movement will now be described. A gear rack 47 is united to the top of the arm 43, between the side 90 portions of the rocker 28, where it is meshed by a gear wheel 48 keyed upon a shaft 49 which passes through transverse journal openings 50 in the said side portions. The top of the same rotary toothed member 48 95 meshes with another relatively stationary rack 51, which is carried by a bar 52 supported at one end in a pair of lugs 53 depending from the supporting block 19. In order to enable the rack 51 to remain in engagement with the gear 48, which moves back and forth in a curved path, the mounting for the bar 52 is so constituted as to permit of a degree of rocking or pivoting. This may be simply accomplished by passing 100 the rear end of the bar 52 through slightly enlarged openings 54 in the lugs 53, between which is an enlargement constituted by a pair of nuts 55 threaded upon the bar. These nuts have convex outer rocking faces and constitute a locking adjustment means for shifting the rack 51 longitudinally. The action of gravity in keeping the rack 51 down upon the gear 48 is supplemented by a compression spring 56 110 interposed between the top of the bar 52 and the upper portion of the block 16. It will accordingly be understood that as the rocking holder 28 oscillates the gear 48 travels upon the relatively stationary rack 115 51 and propels the rack 47 attached to the arm 43, causing the latter to advance and retreat in the holder in the same directions in which the latter is rocked.

The mouthpiece 44 comprises end portions 125 57 having flat faces 58 with air holes 59 therein constituting laterally separated areas of an inclined suction face. Extending between the end portions is a hollow cylindrical portion 60, which is held in a trans- 130

verse barrel 61 united with the end of the tubular arm 43. For convenience of assembly the cylindrical connecting portion 60 is made in two sections united with the respective end portions 57 and having interlocking engagement at their proximate ends, as indicated at 62 in Fig. 5. A tie bolt 63 passes lengthwise through the mouthpiece and through the outer end walls thereof, having a head 64 at one end and a nut 65 at the opposite end to unite the two parts of the mouthpiece together and to hold the same against rotation in the barrel 61. For the latter purpose one of the end portions 57 is preferably provided with an inward projecting pin 66, the point of which may be engaged with any one of a series of sockets 67 in the adjacent end of the barrel. Thus by loosening the nut 65 and slightly separating the sections of the mouthpiece, they may be turned in the barrel and relocked at the desired new adjustment by tightening the nut again, which brings the sections of the mouthpiece together and seats the pin 66 in the appropriate socket 67. A side port 68 in the tubular portion 60 opens into the interior of the tubular arm 43, with which it remains in communication irrespective of the angular adjustment of the suction face produced by turning the mouthpiece in the barrel.

From the foregoing it will be understood that the axis of oscillation of the pneumatic separator is above the plane of the top of the stack of sheets supported on the table 3; that the rocking holder 28 is inclined upward and rearward and has a limited oscillation; and that the arm 43 is inclined downward and rearward and partakes of the same oscillation modified by its longitudinal movement in the holder. The proportioning and adjustment of the parts is intended to be such that the mouthpiece at the conclusion of its downward movement touches, without impact or substantial pressure, the top of the stack a short distance in front of the rear edge of the top sheet; and in this position its suction face or the plane of its ports 59 is inclined upward and rearward, as seen in Fig. 1, so that the suction at the ports turns up the rear edge of the sheet. The holder 28 next rocks forwardly (that is to say toward the front end of the stack) and the separator at the same time moves forward relatively to the holder, so that the combined movement causes the mouthpiece to rise in a curve, which is substantially that which would be described by the rear portion of the sheet if lifted without shifting the sheet. It will be understood that if the arm 43 were fixed to the holder, the arc of movement of the mouthpiece would be such as to tend to drag the top sheet rearward, and this condition is obviated by the double movement which has

been described; at the same time there is no tendency to push the paper forward, the edge being merely turned up and lifted. The turning up of the rear edge of the top sheet preparatory to lifting is very effective in separating it from the sheet beneath, and upon the degree of inclination at which the suction face is presented to the plane of the sheet depends in large measure the satisfactory action of the apparatus. This inclination requires to be adjusted for different grades of paper, depending upon their stiffness or flexibility, and accordingly the provisions heretofore described are made for permitting the mouthpiece to be turned and held in relation to the body of the separator. When the rear edge of the top sheet has been lifted sufficiently to clear the detent, which will presently be described, and to separate the sheet from the sheet below for a substantial distance lengthwise, the suction is cut off by the port 45 passing out of communication with the port 46, whereupon the top sheet is freed from the mouthpiece and the advancing means 5 comes into operation to deliver the sheet to the tapes (not shown).

A detent 69 is located in rear of the pneumatic separator and above and in rear of the stack, being supported and guided upon the guide block 25. The said guide block is formed with upper and lower jaw portions 70 and 71, separated by a substantially horizontal guide slot 72. The forward end of the lower jaw portion 71 is beveled or rounded, as seen at 73, to form a downward and forward sloping extension of the lower wall of the slot bearing 72. In the slot operates a slide block 74 having side retaining flanges 75 engaging the side faces of the guide block 25. Upon the end portions of a rod 76, which passes through the slide block 74, are pivoted the rear ends of side bars 77, the forward portions of which are connected by a rod or shaft 78 bearing a roller 79 to ride upon the slope 73 and side retaining flanges or washers 80 which perform the same function as the flanges 75. In advance of the shaft 78 the side bars 77 are spread laterally, as illustrated in Fig. 3, forming detent fingers 81 the extremities 82 of which are directed forward and reduced in vertical height for facility of insertion between the sheets. It will thus be seen that the carriage part, comprising the slide block 74, is confined to a slot 72 or primary guideway, whereas the other carriage part, including the roller 79, is pivotally connected with the first and adapted to travel up and down on a secondary inclined guideway, represented by the sloping face 73. The power for reciprocating the detent is applied to the rear portion of the carriage and the forward portion is caused to adhere to the descending guide 73

by tension springs 83, the forward ends of which are connected to the detent fingers 81 and their rear ends to pins 84 projecting from the guide block 25.

5. The means for operating the detent includes a pair of bars 85 having rack teeth 86 formed on their forward portions to engage with gear segments 87 fixed on the shaft 49 at opposite sides of the rocking holder 28 of 10 the pneumatic separator, and their rear portions bent downward at 89 and pivotally connected to the shaft 76. The said racks are held up in engagement with the gear segments by means of rollers 88 on the sides 15 of the rocker 28, one of these rollers being indicated in Fig. 1. For purposes of adjustment the bars 85 are preferably made each in two sections with slotted overlapping portions connected by clamping screws 90.

20. By the foregoing means the pneumatic separator and the detent are connected together to move toward and from the stack in alternation, the detent advancing forward and downward as the mouthpiece of the separator moves upward and forward and the mouthpiece descending downward and rearward as the detent retires upward and rearward. Both instrumentalities are timed with the advancing means 5, by connections not necessary to illustrate, so that the advancing means operates when the separator is raised and deenergized and the detent is down upon the balance of the stack, after which the advancing means ceases to operate, the 25 detent retires, and the separator descends to lift the next sheet. As the mouthpiece in this movement approaches the surface of the sheet the port 45 again comes into open relation to the port 46 and the suction current 30 through the mouthpiece is reestablished. The action of the separator in turning up the rear edge of the sheet and then lifting it has already been fully described and need not be repeated.

40. 45. What is claimed as new is:

1. In a sheet feeder having a suitable support for a stack of sheets, a pneumatic separator movably supported over the rear of the stack, and mechanism for moving the 50 same forwardly upward and back, said separator comprising an arm extending in a longitudinal plane and carrying a transverse mouthpiece having a suction face provided with transversely-separated suction ports tilted rearward and upward in its low position so as to turn up the rear edge of the top sheet.

2. In a sheet feeder having a suitable support for a stack of sheets, a pneumatic separator movably supported over the rear of the stack, and mechanism for moving the 60 same forwardly upward and back, said separator having a mouthpiece capable of being turned manually relatively to the balance of the movable separator in order to present its

suction face at a variable rearward and upward inclination to the top sheet.

3. In a sheet feeder having a suitable support for a stack of sheets, a reciprocated pneumatic separator over the rear of the 70 stack having a transverse mouthpiece with separated suction ports presented at a rearward and upward inclination to the surface of the top sheet so as to turn up the rear edge thereof, the mouthpiece being movable 75 on the separator to change the angle of such presentation according to the nature of the paper.

4. In a sheet feeder having a suitable support for a stack of sheets, a pneumatic separator 80 comprising a rocking holder, an arm mounted in the holder in the vicinity of the axis of oscillation and carrying a mouthpiece which is raised and lowered by the rocking movement, the arm being also longitudinally movable in the holder to effect a forward and rearward movement of the mouthpiece, and mechanism for simultaneously rocking the holder and longitudinally moving the arm. 85

5. In a sheet feeder having a suitable support for a stack of sheets, a pneumatic separator comprising a rocking holder, an arm longitudinally movable therein, and a mouthpiece on the arm, combined with means for 90 rocking the holder, racks on the arm and on a relatively stationary part, and rotary toothed means on the arm traveling on the relatively stationary rack and propelling the rack on the arm. 100

6. In a sheet feeder having a suitable support for a stack of sheets, a pneumatic separator comprising a rocking holder, an arm longitudinally movable therein and bearing a rack, a mouthpiece on the arm, a relatively 105 stationary rack, rotary toothed means on the rocking holder meshing with both racks, a tilting support for the relatively stationary rack, and means for holding the same in mesh with said rotary toothed means. 110

7. In a sheet feeder having a suitable support for a stack of sheets, a pneumatic separator comprising a rocking holder, an arm longitudinally movable therein and bearing a rack, a mouthpiece on the arm, a relatively 115 stationary rack, rotary toothed means on the rocking holder meshing with both racks, means for tiltably supporting the relatively stationary rack, and means for adjusting the same longitudinally. 120

8. In a sheet feeder having a suitable support for a stack of sheets, a pneumatic separator comprising a rocking holder, a ported conduit section at the pivotal axis of the holder, a hollow arm longitudinally movable 125 in the holder and ported to communicate with the axial conduit section, a mouthpiece carried by the arm, and mechanism for rocking the holder and longitudinally moving the arm. 130

9. In a sheet feeder having a suitable support for a stack of sheets, a pneumatic separator comprising a rocking holder, a ported conduit section at the pivotal axis of the holder, a hollow arm longitudinally movable in the holder and having a port which is brought into and out of communication with the port in the axial conduit section by the longitudinal movement of the arm in the holder, a mouthpiece carried by the arm, and mechanism for rocking the holder and longitudinally moving the arm. 70
10. In a sheet feeder having a suitable support for a stack of sheets, a pneumatic separator comprising a hollow swinging arm carrying at the rear a transverse barrel, and a mouthpiece formed in separate interlocking sections and comprising two end portions having suction ports and a tubular intermediate portion in the barrel having a port to communicate with the interior of the arm. 80
11. In a sheet feeder having a suitable support for a stack of sheets, a pneumatic separator comprising a hollow swinging arm carrying at the rear a transverse barrel, a mouthpiece formed in separate sections and comprising two end portions having suction ports and a tubular intermediate portion in the barrel having a port to communicate with the interior of the arm, the tubular portion being capable of being turned in the barrel to vary the angle of presentation of the suction ports, and means for locking the sections. 90
12. In a sheet feeder having a suitable support for a stack of sheets, a pneumatic separator comprising a hollow arm carrying at the rear a transverse barrel, a mouthpiece formed in separate interlocking sections and comprising two end portions having suction ports, a tubular intermediate portion in the barrel having a port to communicate with the interior of the arm, and means for tying the sections together and for securing them to the holder against unintended turning movement therein. 100
13. In a sheet feeder having a suitable support for a stack of sheets, the combination with a separator comprising a rocking holder supported over the rear of the stack, an arm longitudinally movable in said holder and carrying a suction mouthpiece, a rack on the arm, a relatively stationary rack, and gearing on the holder meshing with both racks, of a detent movably supported in rear of the separator, and a rack bar connected with said detent and meshing with a portion of the gearing on the rocking holder. 110
14. In a sheet feeder having a suitable support for a stack of sheets, the combination with a separator comprising a rocking holder supported over the rear of the stack, an arm longitudinally movable in said holder and carrying a suction mouthpiece, a rack on the arm, a relatively stationary rack, and gearing on the holder meshing with both racks, of a detent movably supported in rear of the separator, and a rack bar connected with said detent and meshing with a portion of the gearing on the rocking holder. 120
15. In a sheet feeder having a suitable support for a stack of sheets, the combination with means for removing the rear portion of the top sheet, of a part behind and above the stack having a guideway extending forward and downward, a detent-bearing carriage mounted to travel on the guideway, and mechanism for reciprocating the carriage thereon. 130
16. In a sheet feeder having a suitable support for a stack of sheets, the combination with means for removing the rear portion of the top sheet, of a detent adapted to engage the top of the balance of the stack, means for guiding the detent from a position behind and above the stack forwardly and downwardly thereon, and mechanism for reciprocating the detent. 140
17. In a sheet feeder having a suitable support for a stack of sheets, the combination with means for removing the rear portion of the top sheet, of a part behind and above the stack having a guideway extending forward and downward, a carriage mounted to travel on the guideway and having laterally spreading detent fingers, and mechanism for reciprocating the carriage in its guide. 150
18. In a sheet feeder having a suitable support for a stack of sheets, the combination with means for removing the rear portion of the top sheet, of guide means behind and above the stack having primary and secondary guide portions, the latter sloping downward and forward, connected carriage parts guided by the respective guide portions, detent means projecting from the carriage part operative upon the sloping secondary guide portion, and reciprocatory operating means connected with the other carriage part. 160
19. In a sheet feeder having a suitable support for a stack of sheets, the combination with means for removing the rear portion of the top sheet, of a guide block behind and above the stack formed with a slotted guideway having a downward sloping forward extension of its lower wall, a carriage having a rear part slidably confined in said slotted guideway and a forward part adapted to ride on said sloping extension, projecting detent means on the carriage to be brought into contact with the top of the balance of the stack, and reciprocating means connected with the rear portion of the carriage to operate the same. 170

20. In a sheet feeder having a suitable support for a stack of sheets, the combination with means for removing the rear portion of the top sheet, of a part behind and above the stack having a downward sloping guide surface, a detent-bearing carriage movable thereon, mechanism for reciprocating

the carriage, and spring means for constraining it to the guide surface.

Dated, June 30th, 1917.
